UNITED STATES PATENT OFFICE.

WILLIAM A. DE HART, OF TEANECK, NEW JERSEY, ASSIGNOR TO FRANCES ROCKEFELLER KING, OF NEW YORK, N. Y.

ELECTRIC FLATIRON.

Application filed June 16, 1923. Serial No. 645,744.

My invention relates to electrically heated sad irons for laundry and domestic use, and particularly to those of the general character shown and described in Patent No. 5 1,249,638, granted December 11, 1917, to Adele Rockefeller King, and in Patent No. 1,449,201, granted March 20, 1923, to Albert H. Smith.

One object of my invention is to provide 10 a device of the aforesaid character that shall be simple and durable in construction and shall be arranged to exert relatively high pressure between the switch contacts when closed and allow a wide separation between them when open. Moreover, by the arrangement of my invention the switch when closed, is independent of any slight motion or vibration of the handle of the iron and when opened it acts quickly to 20 break the circuit and the metal contacts are separated first while carbon contacts are arranged to take the arc. Thus the main contacts are preserved from rapid deterioration and a good circuit connection insured.

25 Other objects and advantages of my invention are set forth hereinafter and a preferred embodiment thereof is illustrated in the accompanying drawings to which reference may now be had as follows:

30 Figure 1 is a side elevation of an electrically heated iron arranged and constructed in accordance with my invention; the shell being broken away and shown in cross-section, to disclose the interior switch mechanism.

35 Figure 2 is a plan view with the handle and shell removed.

Figure 3 is a view corresponding to Figure 1, except that the switch is shown in its open circuit position.

40 The sad iron illustrated comprises a smoothing iron base 10, a protected electric heating element 11, a spacing plate 12 of insulating material, electrical terminals 13, 45 an electric circuit interrupter 14, a shell 15, a handle 16, and a terminal plug 17.

The iron when not in use is adapted to 50 rest on a stand 18 provided with an overhanging member preferably in the form of a semi-circular band 20, which is arranged to cooperate with a projection 21 of the handle 16 in such manner as to hold the circuit interrupter 14 in a closed circuit position (see Figure 1), when the iron is set 55 on the stand.

The handle comprises a frame 22 which is pivotally connected to the shell of the iron at 23 and is provided with the projection 21 for the purpose above specified. It also has a projection 24 which extends through a suitable slot 25 in the shell of the iron and serves to limit the outward movement of the handle of the iron as shown in Figure 3 and to actuate the circuit interrupter as shown in Figure 1, dependent upon the position of the handle.

The terminals 13 cooperate with the contacts of the plug 17 which is attached to the usual flexible cord conductor 26 and may be detached from the iron at will.

70 The circuit interrupter comprises a pair of stationary contact members, each having a metal main contact 27 and a carbon auxiliary contact 28, and a movable bridging contact member comprising a flexible metal 75 contact 29 with auxiliary carbon contacts 30 at its respective ends.

The bridging contact is attached to a block or support 31 which is slidably mounted in a guide 32 and is actuated by 80 a toggle link 33, one end of the link being connected to the sliding block 31 and its opposite end being connected to a compressible link 34 which in turn is pivoted on a fixed support 35. When the switch is closed the toggle is overset with a spring 36, which forms a part of the compressible link, under tension.

85 On the other hand, when the switch is open, the spring expands and collapses the 90 toggle sufficiently to widely separate the switch contacts.

The toggle actuating mechanism is governed by the finger or lever 24 which is attached to the handle yoke 22 at 38 and is 95 shaped to extend downwardly and forwardly to connect to the toggle link 33 by a loose pin and slot connection. The finger 24 is provided with slotted down-turned ears or lugs 37 which are spaced to straddle link 33. 100 The ends of a pin 39 extending through a longitudinal slot in the link 33 loosely engage the slots of ears or lugs 37.

A flat spring 40 rigidly attached to the handle frame 22 at 38 extends between the 105 shell 15 and the frame 22 and engages the upper surface of the shell for raising the handle frame into the position shown in Figure 3, when hand pressure is released.

The toggle link 34 is pivotally connected 110

to the toggle link 33 at 41 and is connected by a pin and slot connection at 42 to the stationary pivot 35, the spring 36 surrounding the link 34 and pressing the link outward from the stationary pivot.

When the iron is in use the handle may vibrate considerably due to variations in pressure upon it, without in any way tending to open the circuit interrupter or release the pressure between the cooperating contact members. This is evident because as already explained, the toggle is overset and there is no tendency for it to open until tripped by the upward movement of the ears 37 on the pin 39, the slots in ears 37 permitting a considerable up and down movement of the handle before actuating the toggle link to open the circuit.

When the pressure of the hand of the user is entirely released from the handle the flat spring 40 swings the handle upward on its pivot and the upward movement of the finger 24 trips the toggle and quickly opens the switch, the spring 36 serving to accelerate the opening of the contacts when released, as well as to press them together when the switch is closed.

When the switch contacts 27 and 29 are in engagement and the interrupter closed, the electric heating circuit is established from one of the terminals 13 to the other through the electric heater 11 and the interrupter 14.

Attention is particularly directed to the fact that the bridging contact member 29 is not only flexible but is also pivotally or loosely mounted on the block 31 and is electrically insulated therefrom. In this way the contact member is adjustable and seats itself in close engagement with the stationary contact members 27 when the interrupter is closed.

The arrangement of the actuating mechanism is such as to provide a rapid or quick break operation of the interrupter as already explained, and this feature is of importance to my invention since it tends to prevent an arc being established in breaking the circuit.

If it is desired to have the heating element of the iron in circuit, while the iron is not in use, it is only necessary to set the iron on the stand 18 with the projection 21 under the loop 20 of the stand. Attention is directed to the fact, however, that unless the iron is on the stand it cannot be energized except when the handle is being pressed downwardly by the hand of the user. The iron is thus rendered unusually safe and the possibility of fires are minimized if not entirely obviated.

It is of course a well known fact that great numbers of fires have resulted from electric irons being left in circuit, standing on a table or board and while various switches for interrupting the circuit have been provided, it

has been my aim to make a commercially operative arrangement capable of continued and satisfactory operation.

The arrangement for holding the switch closed when the iron is on the stand, forms no part of my invention, it being claimed in the Albert H. Smith Patent No. 1,449,201, granted to F. R. King on March 29, 1923.

A structure of preferred form and construction has been illustrated and described for the purpose of showing a way in which this invention may be used, but the inventive thought upon which this application is based, is broader than this illustrative embodiment thereof, and I therefore intend no limitations other than those imposed by the appended claims.

What I claim is:

1. The combination with a body, and a handle movably attached thereto, of a circuit interrupter including a movable contact member, a pair of toggle links acting upon said movable contact member adapted to force the circuit interrupter closed when overset and an actuating arm arranged and adapted to be moved in response to pressure on the handle for setting the toggle and closing the interrupter when pressed downwardly and for releasing the toggle and opening the interrupter when moved upwardly.

2. The combination with a body, and a handle movably attached thereto, of a circuit interrupter including a movable contact member, a pair of toggle links acting upon said movable contact member adapted to force the circuit interrupter closed when overset, an actuating arm arranged and adapted to be moved in response to pressure on the handle for setting the toggle and closing the interrupter when pressed downwardly and for releasing the toggle and opening the interrupter when moved upwardly, and resilient means for moving the handle in an upward direction when pressure is removed therefrom.

3. The combination with a body, and a handle movably attached thereto, of a circuit interrupter including a movable contact member, a pair of toggle links acting upon said movable contact member adapted to force the circuit interrupter closed when overset and an actuating arm attached to the handle and connected to one of the toggle links by a lost motion connection, for setting the toggle and closing the interrupter.

4. The combination with a body, and a handle movably attached thereto, of a circuit interrupter including a movable contact member, a pair of toggle links acting upon said movable contact member adapted to force the circuit interrupter closed when overset, an actuating arm arranged and adapted to be moved in response to pressure on the handle for setting the toggle and

closing the interrupter when pressed downwardly and for releasing the toggle and opening the interrupter when moved upwardly, and a spring on the outside of the shell and attached to the handle for moving the handle upwardly when released.

5. The combination with a body, and a handle movably attached thereto, of a circuit interrupter including a movable contact member, a pair of toggle links acting upon said movable contact member adapted to force the circuit interrupter closed when overset, an actuating arm arranged and adapted to be moved in response to pressure 10 on the handle for setting the toggle and closing the interrupter when pressed downwardly and for releasing the toggle and opening the interrupter when moved upwardly, one of said toggle links being supported by a pin and slot connection and spring-pressed to make it act as a compressible member.

6. The combination with a body, and a handle movably attached thereto, of a circuit interrupter including a movable contact member, a pair of toggle links acting upon said movable contact member adapted to force the circuit interrupter closed when overset, an actuating arm arranged and adapted to be moved in response to pressure 25 on the handle for setting the toggle and closing the interrupter when pressed downwardly and for releasing the toggle and opening the interrupter when moved upwardly, one of said toggle links being compressible and arranged in such manner as to press the contacts together when the toggle is overset and to cause a quick break when the toggle is tripped.

- 40 7. The combination with a body, and a handle movably attached thereto, of a circuit interrupter including a movable contact member, a pair of toggle links acting upon said movable contact member adapted to force the circuit interrupter closed when overset, an actuating arm arranged and adapted to be moved in response to pressure 45 on the handle for setting the toggle and closing the interrupter when pressed downwardly and for releasing the toggle and opening the interrupter when moved upwardly, and resilient means for moving the handle in an upward direction when pressure is removed therefrom, one of said toggle links being compressible and arranged in 50 such manner as to press the contacts together

when the toggle is overset and to cause a quick break when the toggle is tripped.

8. The combination with a body, and a handle movably attached thereto, of a circuit interrupter including a movable contact member, a pair of toggle links adapted to force the circuit interrupter closed when overset, an actuating arm arranged and adapted to be moved in response to pressure 60 on the handle for setting the toggle and closing the interrupter when pressed downwardly and for releasing the toggle and opening the interrupter when moved upwardly, one of said toggle links being composed of a rigid member pivoted on a fixed support by a pin and slot connection, and a spring surrounding the rigid member and tending to press it away from the fixed support and the other of said toggle links being 65 connected to the movable contact member of the circuit interrupter, the arrangement being such that the contacts are forcibly pressed together and wear between them is 70 taken up by the spring-pressed link.

9. The combination with a body supporting a circuit controlling switch having stationary and movable contact members, of a pair of toggle-jointed links, one of which is connected with said body and the other of which is operatively connected with said movable contact member, and a controlling handle movably attached to said body and having operative connection with said links.

10. The combination with a body supporting stationary and movable contact members of a controlling switch, and a handle movably attached to said body, of a pair of toggle-jointed links connected respectively with said body and said movable contact 90 member, and an actuating arm attached to said handle and operatively connected with said links.

11. The combination with a body supporting stationary and movable contact members 100 of a circuit controlling switch, and a handle movably attached to said body, of a pair of toggle-jointed links connected respectively with said body and said movable contact member, an element operatively connecting 105 said handle with one of said links, and a spring acting upon said handle and resiliently supporting it in normal raised position upon said body.

In witness whereof, I have hereunto set 110 my hand this 16th day of May, 1923.

W. A. DE HART.
